SPRAY HEAD

Benjamin C. Beeler, Sepulveda, Calif.
(19922 Hemingway, Canoga Park, Calif. 91306)

Filed Aug. 3, 1972, Ser. No. 277,560

Term of patent 14 years

Int. Cl. D23—01

U.S. Cl. D23—34

FIG. 1 is a perspective view of the spray head showing my new design;

FIG. 2 is a front elevational view thereof;

FIG. 3 is a side elevational view thereof;

FIG. 4 is a rear elevational view thereof;

FIG. 5 is a top plan view thereof;

FIG. 6 is a bottom plan view thereof; and

FIG. 7 is a perspective view of a modified form of the spray head shown in FIG. 1.

I claim:

The ornamental design for a spray head, substantially as shown and described.
